DATA RECORD CARD FOR RECORD CARD CONTROLLED APPARATUS

Daniel L. Miller and Terry B. Prince, Indianapolis, Ind.,
assignors to Bell Telephone Laboratories, Incorporated,
Murray Hill and Berkeley Heights, N.J.

Continuation-in-part of design application Ser. No.
17,767, June 4, 1969, which is a continuation-in-part of
design application Ser. No. 11,273, Apr. 3, 1968, both
abandoned. This application Jan. 19, 1970, Ser. No.

20,995

Term of patent 14 years

Int. Cl. D14—02

U.S. Cl. D26—14

FIG. 3

FIG. 2

FIG. 1

FIG. 6

FIG. 5

FIG. 4

FIG. 1 is a front view of a data record card for record card controlled apparatus, embodying our new design;

FIG. 2 is a rear view of the first embodiment of the data record card;

FIG. 3 is a side view of the first embodiment of the data record card, the opposite side having substantially the same appearance;

FIG. 4 is a front view of a second embodiment of a data record card embodying our new design;

FIG. 5 is a rear view of the second embodiment of the data record card; and

FIG. 6 is a side view of the second embodiment of the data record card the opposite side having substantially the same appearance.

This application is a continuation-in-part of application Ser. No. D. 17,767, filed June 4, 1969, which is a continuation-in-part of application Ser. No. D. 11,273, filed

Apr. 3, 1968. Both the parent applications have been abandoned subsequent to the filing of the continuation-in-parts thereof.

We claim:

The ornamental design for a data record card for record card controlled apparatus, substantially as shown and described.
